(57) **CLAIM**

The ornamental design for a sea shelling bag, as shown and described.

DESCRIPTION

FIG. 1 is a front perspective view of the sea shelling bag showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view showing the sea shelling bag in use.

The broken lines shown in the drawings illustrate portions of the sea shelling bag that form no part of the claimed design.

The broken lines in FIG. 8 showing the sea shelling bag in use illustrates environment and forms no part of the claimed design.
